DESIGN FOR A COMBINED RADIATOR GUARD AND COVER THEREFOR

George B. Warner, New York, N. Y.

Application July 30, 1932. Serial No. 44,503

Term of patent 7 years

To all whom it may concern:

Be it known that I, GEORGE B. WARNER, a citizen of the United States, residing at New York, in the county of New York and State of New York, have invented a new, original, and ornamental Design for a Combined Radiator Guard and Cover Therefor, of which the following is a specification, reference being had to the accompanying drawing, forming part thereof.

Figure 1 is a front elevation of the radiator guard with its cover.

Figure 2 is a section on line 2—2 of Figure 1.
I claim:

The ornamental design for a combined radiator guard and cover therefor, as shown.

GEORGE B. WARNER.
